UNITED STATES PATENT OFFICE.

WALTER A. ADAMS, OF ROCHESTER, NEW YORK, ASSIGNOR TO LEWIS INVISIBLE STITCH MACHINE COMPANY, OF ST. LOUIS, MISSOURI, A CORPORATION OF DELAWARE.

PRESSER FOOT.

Application filed September 4, 1924. Serial No. 735,880.

To all whom it may concern:

Be it known that WALTER A. ADAMS, a citizen of the United States, residing at Rochester, in the county of Monroe and 5 State of New York, has invented certain new and useful Improvements in Presser Feet, of which the following is a specification.

This invention relates to new and useful 10 improvements in presser feet for sewing machines generally, although more particularly to presser feet for use in connection with blind stitch sewing machines adapted for use in felling operations, the preferable type 15 of sewing machine being illustrated in the co-pending application of Charles W. Mueller for improvements in stitch forming mechanism, filed February 14, 1924, Serial No. 692,696.

20 In felling operations, such as for instance, on the bottoms of coats, trousers or the like, the super-imposed layer, that is, the fell is very often previously bound by a binding which is secured to the marginal 25 edge portion by a line of through-and-through stitches. In blind stitching the fell to the base fabric, it is desirable to position the needle thread, which connects the penetrant needle thread loops, under the marginal edge portion of the binding, whereby 30 the latter will conceal said needle thread.

The principal object of my invention is, therefore, to provide a presser foot with a device for lifting the marginal edge portion 35 of the binding whereby the needle of the blind stitch machine will penetrate the superimposed layer or fell at a point directly adjacent the through-and-through stitches which secures the binding to said fell, whereby 40 by the marginal edge portion of said binding will subsequently cover the needle thread lying between the needle thread loops forming the blind stitches.

Another object of the invention is to provide a presser foot with an edge guide arranged in cooperative relation with the lifting device whereby the edge portion of the fell will be elevated sufficiently to permit the needle to pass through the fell and into 50 and out of the upper face of the base layer

without re-entering the edge portion of the fell.

Another object of the invention is to provide an edge guide for the purpose set forth which is adjustable to accommodate bindings of different widths without disturbing the relationship between the elevated edge portion of the fell and the needle of the sewing machine.

A still further object of the invention is 60 to provide a combined needle guide and edge-lifting device from a single piece of metal and supporting the same on the presser foot in such a manner as to insure the needle guide always being in proper position 65 relative to the lifting device.

With the above and other objects in view which will more readily appear as the nature of the invention is better understood, the same consists in the novel construction, 70 combination and arrangement of parts hereinafter more fully described, illustrated and claimed.

In the accompanying drawings which show one form of my invention,

Figure 1 is a plan view of a presser foot showing the application of my invention,

Figure 2 is a similar view but without the fabric,

Figure 3 is a bottom plan view of the 80 presser foot,

Figure 4 is an enlarged detail sectional view taken on the line 4—4 of Figure 3,

Figure 5 is an enlarged detail sectional view taken on the line 5—5 of Figure 2,

Figure 6 is an enlarged perspective view of my combined needle guide and lifting device,

Figure 7 is a view showing in perspective the various parts forming the edge 90 guide, and

Figure 8 is an enlarged sectional view on line 8—8 of Figure 1 showing more or less diagrammatically, the relative positions of the parts.

Like reference numerals designate corresponding parts throughout the several figures of the drawings.

In the accompanying drawings the presser foot 5 includes a body portion 6 having at 100

taching ears 7—7 integral therewith. Extending rearwardly from the front edge 8 of the presser foot is a centrally disposed fabric guiding slot 9, the inner portion 5 thereof being angularly offset as at 10 to provide an outlet for the edge portion of the fell. A feeding mechanism, not shown, feeds the work rearwardly as indicated by the arrow in Figure 1, and consequently the 10 line of feed is coincident with the major axis of the fabric guiding slot 9. This slot 9 forms resultant right and left forwardly extending arms 11 and 12 respectively. In blind stitch machines for doing this class 15 of work, the needle 13 oscillates about a horizontal axis located above the inner end portion 10 of the slot 9, the axis being disposed at an angle to the line of feed. Consequently, the needle oscillates in a vertical 20 plane disposed at an angle to the line of feed, this angle being shown in the drawings as at 45°. It will however be understood that the needle may be oscillated at any other desired angle relative to the line of feed.

25 In felling the bottoms of coats, trousers or the like, the edge portion of the fabric F is first covered by the binding or piping 15 which is secured to the fabric by a line of through-and-through stitches 16, and then 30 this fabric is folded to form a resultant base layer 17 and a superimposed layer or fell 18. The function of the present presser foot is to assist in blind stitching the superimposed layer or fell 18 to the base layer 17, in such 35 a manner that the needle will cause its penetrant needle thread loops to enter the superimposed layer or fell 18 under the marginal portion of the binding 15 and thence into and out of the upper face of the base layer 40 17. In this type of blind stitch machine, I preferably employ a vertical oscillatory plunger 19 which is timed to make one complete reciprocation for each oscillation of the needle, the high points of said plunger 45 reciprocations being preferably raised and lowered alternately so as to alternately elevate the base layer into the path of the needle 13 during every other oscillation thereof. By means of this plunger it will 50 be observed that the base layer is engaged by the needle thread during every other oscillation of the needle. This avoids puckering of the base layer on the fair side thereof which would be the case if the needle engaged said base layer during each oscillation 55 thereof.

In order to insure the needle entering the superimposed layer or fell 18 under the marginal edge portion of the binding 15 and 60 adjacent the line of through-and-through stitches 13, I have provided a presser foot with an edge-lifting device 20 which in this instance is shown as having an integral shank 21, the latter being formed with a groove 22 65 in its upper face forming a needle guide.

The shank 21 is seated in a groove formed in the upper face of the right hand arm 11 and is held therein by a screw 23. The shank 21 is disposed in a plane at right angles to the direction of needle penetration, or in 70 other words, at an obtuse angle relative to the line of feed. The major axis of the groove 22 which forms the needle guide is coincident with the movements of the needle. The plunger 19 operates through the slot 9 75 of the presser foot and is located directly in rear of the needle guide 22. The lifting device 20 is formed with an upwardly and rearwardly inclined guiding surface 24, the upper end 25 thereof being disposed at a point 80 adjacent the end of and in a plane above the point of needle penetration, that is, above the plane of the groove 22.

The fabric is fed through the sewing machine as shown in Figures 1 and 8 of the 85 drawings, the fell 18 being disposed under the right hand arm 11 of the presser foot and the marginal edge portion thereof including the binding 15 being bent upwardly into the groove 9 and thence downwardly 90 through the offset end 10 thereof and finally passing under the presser foot.

The material is fed rearwardly and during its passage the edge-lifting device 20 is engaged by the marginal portion of the binding and elevated above the path of the needle whereby the point of the needle will enter the fell directly under said marginal portion of the binding and adjacent the line of through-and-through stitches 16.

In order to guide the marginal portion of the fell, that is, that portion including the binding 15, whereby the needle will penetrate the fell and thence enter and emerge from the upper face of the base fabric without re-entering the fell, I have provided an edge guide which I have indicated as a whole by the reference numeral 26. This edge guide comprises a shelf 27 which extends parallel with the fabric guiding slot 9 and is disposed in spaced relation to the lifting device 20 so as to permit the fell to pass upwardly therebetween and be supported by said shelf. This shelf is provided with an overhanging lip 28 and a vertically disposed connecting wall 29, the latter serving to crowd the binding towards the lifting device 20 whereby the latter will with certainty elevate the marginal edge of the binding for the purpose previously described.

The shelf is provided with a supporting shank 30 arranged at substantially 45° relative to the plane of the shelf. This shank 30 is provided with an elongated hole 31, the elongation being in the direction of its length and consequently parallel to the plane of the needle oscillation. An attaching screw 32 passes through a collar 33, thence through the opening 31 and has threaded engagement with the left arm 8 of the presser foot. By 130

means of the elongated hole 31, the guide may be adjusted to accommodate bindings of different widths without disturbing its co-operative relation with the edge-lifting device 20, the movement of the edge guide during its adjustment being in a plane parallel to the plane of needle oscillation and consequently also in a direction transverse to the line of feed. In order to further retain the upturned fell in proper working position, I have provided a second edge guide 34 which is disposed below the edge guide 26 and is secured through a slot 35 to the presser foot by the same screw 32. Thus the second guide 34 may be adjusted relative to the lifting device 20 to provide a slot therebetween to freely receive a fell of a given thickness, and the edge guide 26 may be adjusted independently of said second guide 34 to accommodate bindings of different widths, the operative edge of the guide 34 engaging the fell adjacent the binding thereof.

It is of course to be understood that the details of structure and arrangement of parts may be variously changed and modified without departing from the spirit and scope of my invention.

I claim:

1. In a presser foot for blind stitch felling machines, the combination of a body portion having a rearwardly extending slot for guiding a previously bound fell, and an edge lifting device secured to said body portion and disposed within the slot for raising the marginal portion of the binding of the fell.

2. In a presser foot for blind stitch felling machines, the combination of a body portion having a rearwardly extending slot for guiding a previously bound fell, and an edge lifting device secured to said body portion and disposed within the slot for raising the marginal portion of the binding of the fell, said device having the upper fell-engaging surface extending upwardly and rearwardly.

3. In a presser foot for blind stitch felling machines, the combination of a body portion having a rearwardly extending slot for guiding a previously bound fell, and an edge lifting device secured to said body portion and disposed within the slot for raising the marginal portion of the binding of the fell, said device having a shank detachably secured to said body portion of the foot and formed with a needle guiding groove.

4. In a presser foot for blind stitch felling machines, the combination of a body portion having a rearwardly extending slot for guiding a previously bound fell, and an edge lifting device secured to said body portion and disposed within the slot for raising the marginal portion of the binding of the fell,

said device having a shank detachably secured to said body portion of the foot and formed with a needle guiding groove, said device having its upper fell-engaging surface extending upwardly and rearwardly from a point in advance of the needle guiding groove to a point adjacent the rear end of and in a plane above said groove.

5. In a presser foot for blind stitch felling machines, the combination of a body portion having a rearwardly extending slot for guiding a previously bound fell, and an edge lifting device secured to said body portion and disposed within the slot for raising the marginal portion of the binding of the fell, and an eye guide for the fell secured to the body portion and disposed in spaced parallel relation to said lifting device.

6. In a blind stitch felling machine, the combination with a presser foot having a rearwardly extending slot for guiding a previously bound fell, of a device secured to the foot at one side of the slot for raising the marginal portion of the binding of the fell, a needle oscillating in a plane at an angle to the major axis of said slot for penetrating the fell under the raised marginal portion of the binding, and an edge guide for the fell secured to the presser foot at the other side of said slot.

7. In a blind stitch felling machine, the combination with a presser foot having a rearwardly extending slot for guiding a previously bound fell, of a device secured to the foot at one side of the slot for raising the marginal portion of the binding of the fell, a needle oscillating in a plane at an angle to the major axis of said slot for penetrating the fell under the raised marginal portion of the binding, and an edge guide for the fell secured to the presser foot at the other side of said slot, said guide being provided with a shelf for supporting the fell above the base layer for entrance by the needle.

8. In a blind stitch felling machine, the combination with a presser foot having a rearwardly extending slot for guiding a previously bound fell, of a device secured to the foot at one side of the slot for raising the marginal portion of the binding of the fell, a needle oscillating in a plane at an angle to the major axis of said slot for penetrating the fell under the raised marginal portion of the binding, and an edge guide for the fell secured to the presser foot at the other side of said slot, said guide being mounted on the foot for adjustments in a plane parallel to the plane of needle oscillation.

9. In a presser foot for blind stitch felling machines, the combination of a body portion having a rearwardly extending slot for guiding a previously bound fell, an edge-lifting device secured to said body portion

at one side of the slot for raising the marginal portion of the binding of the fell, an edge guide for the fell secured to the body portion of the foot on the other side of the slot and adjustable towards and from said lifting device, and a second guide for the fell for engaging the latter adjacent the

binding and supported on said body portion on the opposite side of the slot from said lifting device.

In testimony whereof I hereunto affix my signature.

WALTER A. ADAMS.
